Term of patent 7 years

Int. Cl. D26—05

U.S. Cl. D48—20 R

FIG. 1 is a side elevation of a boudoir lamp showing my new design;

FIG. 2 is a plan view thereof on a reduced scale;

FIG. 3 is a bottom view on the same scale as FIG. 2;

FIG. 4 is a top perspective view of the lamp shade on a reduced scale, the remainder of the lamp being omitted for convenience of illustration; and

FIG. 5 is a top perspective view of the base on a reduced scale, the remainder of the lamp being omitted for convenience of illustration.

What I claim is:

The ornamental design for a boudoir lamp, as shown and described.
